CLAIM

The ornamental design for a litter scoop holder, as shown and described.

DESCRIPTION

FIG. 1 is a front view of a litter scoop holder showing my new design;

FIG. 2 is a back view thereof;

FIG. 3 is a top view thereof;

FIG. 4 is a left side view thereof; and,

FIG. 5 is a right side view thereof.

The broken-line disclosure of the litter scoop in the views is for illustrative purposes only and forms no part of the claimed design.
